DEPOSIT BOX

David I. White III and John H. Giles, Decatur, Ala.

Application April 29, 1954, Serial No. 30,253

Term of patent 14 years

(Cl. D58—12)

FIG. 1

To all whom it may concern:

Be it known that we, David I. White III and John H. Giles, citizens of the United States and residing at Decatur, Alabama, have invented a new, original, and ornamental Design for a Deposit Box, of which the following is a specification, reference being had to the accompanying drawing, forming a part thereof.

Fig. 1 is a front elevational view of a deposit box showing my new design.

Fig. 2 is a side elevational view thereof.

Fig. 3 is a rear elevational view; and

Fig. 4 is a top view.

We claim:

The ornamental design for a deposit box, as shown.
